UNITED STATES PATENT OFFICE

119,601

DESIGN FOR A SYRINGE BAG

Mary Marjorie Smith, Lancaster, Pa., assignor to Armstrong Cork Company, Lancaster, Pa., a corporation of Pennsylvania

Application July 12, 1939, Serial No. 85,965

Term of patent 14 years

To all whom it may concern:

Be it known that I, Mary Marjorie Smith, a citizen of the United States, residing in Lancaster, county of Lancaster and Commonwealth of Pennsylvania, have invented a new, original, and ornamental Design for Syringe Bags, of which the following is a specification, reference being had to the accompanying drawing, forming a part thereof, in which

The opposite side of the syringe bag from that shown in the drawing has substantially the same appearance as the side illustrated.

I claim:

The ornamental design for a syringe bag, substantially as shown and described.

MARY MARJORIE SMITH.
